COIN COLLECTING APPARATUS

Walter A. Bockistch, Chicago, Ill., assignor to
Western Electric Company, Incorporated, New
York, N. Y., a corporation of New York

Application July 11, 1936, Serial No. 90,086

7 Claims. (Cl. 194—16)

This invention relates to coin collecting apparatus, particularly of the type for use in a telephone pay station.

In the usual type of telephone coin collector 5 as exemplified in the disclosure of the O. F. Forsberg U. S. Patent 1,043,219, issued November 5, 1912, deposited coins after striking a coin trigger are temporarily retained upon a coin trap and subsequently directed into a collect chute 10 or a refund chute, depending upon whether the desired telephone connection is established. The purpose of the coin trigger is to close a circuit to place under the control of the remote operator a polarized electromagnet which when operated 15 causes a pivotal armature thereof to be actuated which when operated in one direction effects a refund of the deposited coin and when operated in the opposite direction collects the deposited coin. The coin trigger is usually pivoted externally of the coin passage and is normally maintained in its non-operated position by a suitable counterbalance. The arrangement is 20 also such that the coin trigger after operation by a deposited coin will not be restored until the 25 electromagnet is operated.

Objects of this invention are to provide simple and effective resilient stop means and a mounting therefor for cushioning the trigger in its movement in either direction in order to improve 30 the operating characteristics thereof and further to minimize the danger of false operation of the trigger in the absence of a deposited coin.

In accordance with the above objects, the invention contemplates, in one embodiment thereof, 35 a flat spring plate having integral leaf spring extensions with an end of each extension predeterminedly operatively positioned relative to the coin trigger to provide respectively cushion or resilient stop means for the trigger for each direction of movement thereof. The plate is adapted to surround the shank of a pivot screw for the electromagnet armature and is clamped against a stationary support by the screw head. A straight edge on the plate and an extension 45 thereof closely associated with surfaces of the support serve to supplement the clamping action of the screw to maintain the plate and thereby the leaf spring extensions integral therewith in predetermined operative positions relative to the 50 trigger.

The invention will be better understood by reference to the following detailed description taken in connection with the accompanying drawing, in which

55 Fig. 1 is a fragmentary view, partly in section,

of the central part of a telephone coin collecting apparatus embodying the features of this invention;

Fig. 2 is a fragmentary vertical section, on an enlarged scale, taken along the line 2—2 of 5 Fig. 1;

Fig. 3 is a fragmentary vertical section taken along the line 3—3 of Fig. 2, and

Fig. 4 is an elevational view on an enlarged scale of the spring plate for cushioning the coin 10 trigger in its movement in either direction.

Referring now to the drawing, Fig. 1 shows a portion of a telephone coin collector of the general type disclosed in the above mentioned Forsberg patent, to which reference is made for 15 further details as to its construction and mode of operation. A coin deposited by a subscriber after passage through a coin chute 10 (Fig. 1) drops into a coin hopper 11, actuates a coin trigger 12 and is temporarily retained upon a 20 coin trap 13. The actuation of the trigger 12 releases a spring 14 of a contact spring pile-up 17 mounted on an upwardly extending portion 18 of a bridge plate 19 which extends between coils of a polarized electromagnet 20. The release of 25 the spring 14 enables a circuit to be closed through the windings of the electromagnet 20 whereby the remote central office operator by an arrangement disclosed in the Forsberg patent 30 may subsequently cause the coin on trap 13 to be directed into a refund or a collect chute depending upon the polarity of the current applied to the electromagnet 20.

The electromagnet 20 comprises coils 21 and 35 22 having magnetic material cores and is mounted on a piece of magnetic material forming a part of the magnetic circuit. The cores terminate in pole pieces 25 and 26, which extend through the bridge plate 19. A piece of magnetic material 27 extends from the piece upon 40 which the coils are mounted to just under the middle portion of an armature 28 to complete the magnetic circuit.

A yoke shaped metallic piece 29 (Fig. 3) is 45 fixed to the upper face of the armature 28, the yoke piece having narrow arms extending down the side of the armature which provide bearings into which the inner ends of trunnion screws 32 fit to support the armature pivotally near the middle, the screws being supported in 50 the bridge plate 19.

Mounted on the trunnion screws 32 and positioned just above the armature 28 is a metallic member 33 provided with an arm 34 which extends downwardly adjacent the coils 21 and 22. 55

The arm 34 is forked at its lower end 35 (Fig. 1) to engage an extension 36 of a supporting vane 39 for the coin trap 13. Short downwardly projecting arms 40 (Fig. 2) of the member 33 are adapted to contact with the armature 28 after a small movement of the armature. Other downwardly projecting arms 41 of the member contact with the bridge plate 19 and act as stop members for the member 33.

Independently movable armature restoring arms 42 and 43 are also pivotally mounted on the trunnion screws 32 above the member 33 which is movable with the armature 28 and are adapted to be moved by the member, the arms each having a lug 46 (Fig. 2) on its lower surface in contact with the upper surface of the member 33. Springs 47 (Fig. 1) are attached to the arms 42 and 43, at one end and to extensions of the bridge plate 19 at the other end. These springs 47 function through the restoring arms 42 and 43 to restore the armature 28 to its normal position after movement in either direction. The restoring arms 42 and 43 are provided with downwardly extending end arms 48 (Fig. 2) which contact the electromagnet pole pieces 25 and 26 to act as stop members.

The spring 14 of the contact spring pile-up 17 is tensioned to force the other springs together and against a bifurcated angle piece 49 (Fig. 3) which together with the coin trigger are pivoted on a rod 50 which is supported on two lugs 53 and 54 (Fig. 2) which are extensions of the bridge plate 19.

At its free end the tensioned pile-up spring 14 is provided with a downwardly projecting extension 55 adapted to cooperate with a cam portion 56 of the trigger 12. When the trigger is in its upper and normal position its cam portion 56 contacts with the spring extension 55 to restrain the spring 14 from forcing the contacts together thereby holding the circuit open. When the trigger is struck by a deposited coin it moves to its lower and operated position, the cam portion 56 of the trigger releasing the spring 14, which then being unrestrained, forces the contact spring of the pile-up 17 together and causes a circuit to be established through the coils 21 and 22 of the electromagnet 20. Thereafter the extension 55 of the spring 14 acts as a pawl to hold the trigger in its lowered position. The circuit established is under the control of the remote operator who may now complete the energization circuit through the electromagnet whereby the armature 28 is moved either clockwise or counter-clockwise about its trunnion screws 32 depending on whether the deposited coin is to be refunded or collected.

Furcations 58 and 59 of the bifurcated angle piece 49 (Fig. 3) are provided with bent over portions 60 adapted to contact with the restoring arms 42 and 43, respectively, so that if either restoring arm is moved upwardly furcations 58 and 59 of the angle piece 49 are also moved upwardly and the upright portion of the angle piece 65 is forced against the contact spring pile-up 17 thereby moving extension 55 of the spring 14 away from the cam portion 56 of the coin trigger 12, the trigger thereupon returning to its normal position due to the weight of a counterbalance 70 portion 61 of the trigger.

In order to minimize the danger of false operation of the coin trigger 12 by blows on the housing and further to reduce the danger that the trigger will stick to the adjacent bridge plate 75 and thus fail to restore at the proper time, im-

proved resilient stop means and a novel mounting therefor are provided to limit both the upward and downward movement of the trigger. The means preferably used to accomplish this comprises an irregularly shaped resilient plate 62 (Fig. 4) of suitable metal, which in the present embodiment is formed of phosphor bronze of adequate thickness and resiliency. Extending from and integral with the spring plate 62 are arms or leaf springs 63 and 64, each end of which 10 serves as a cushion or resilient stop means for movement of the trigger in one direction. The plate 62 is formed with an aperture 65 adapted to receive the shank of the rear armature trunnion screw 32. Also, integral with the plate is 15 a third arm 68 extending at right angles to the leaf spring arm 64 and between these arms the plate is formed with a straight edge 69.

As clearly shown in Figs. 2 and 3 the resilient plate 62 is clamped to the bridge plate 19 by the 20 head of the rear trunnion screw 32, the shank of the screw passing through the aperture 65 of the plate and the arm 68 and the straight edge 69 are in close or abutting relation with a vertical edge and lower face, respectively, of an extension 70 of the bridge plate. The leaf spring arm 63 it will be observed, as viewed in Fig. 2, is bent backwards and to the right of the edge of the bridge plate extension 70 which is opposite the edge thereof with which the arm 68 of the 30 plate 62 is associated. The end of the spring arm 63 in the normal or upper position of the trigger 12 contacts with the lower edge of an arm of the counterbalance portion 61 of the trigger to provide a resilient stop member for the trigger at 35 the end of its restoring movement. A stop member for the trigger at the end of its movement in the opposite direction is provided by the leaf spring arm 64 of the resilient plate 62 which extends horizontally along the rear face of the 40 bridge plate 19 with its free end unsupported thereby and disposed in the path of a portion 71 of the trigger. It will be apparent from Figs. 2 and 3 that the leaf spring arm 64 provides a resilient stop member for the trigger in its downward movement to its operated position since the portion 71 of the trigger will strike the spring arm when the trigger is knocked downwardly by 45 a deposited coin.

It will be apparent that the above described 50 resilient stop means for positively cushioning the trigger in its movement in either direction constructed from an integral resilient plate is simple and economical to manufacture. Also that the leaf spring arms may be easily adjusted relative 55 to the portions of the trigger with which they contact to provide the desired cushioning effect. Furthermore, due to the arm and the straight edge which are closely associated with surfaces 60 of the stationary bridge plate, which arrangement supplements the clamping action of the pivot screw head for the armature on the resilient plate, the leaf spring arms will be positively maintained in their adjusted operated positions relative to the trigger. In addition, the particular construction of the stop means and the method 65 of mounting it in position afford an arrangement whereby it may be readily mounted on the coin collector apparatus, or replaced, and also without providing special means for fixing 70 it in position.

Although the embodiment of this invention as herein illustrated and described is particularly well adapted for use in connection with telephone pay station coin collectors, it should be 75

understood that the invention is capable of other applications and should be limited only by the scope of the appended claims.

What is claimed is:

5. 1. A coin collector comprising a coin passage, a pivotal coin trigger having an arm projecting into said passage for operation by a deposited coin, said trigger having a counterbalance, and a fixed flat resilient plate having integral extensions disposed substantially at right angles to each other providing resilient stop means for said trigger for trigger movement in either direction. 5
10. 2. A coin collector comprising a coin passage, a support, a pivotal coin trigger carried by said support having an arm projecting into said passage for operation by a deposited coin, said trigger having a counterbalance, a flat resilient plate clamped to said support having integral extensions providing resilient stop means for said trigger for trigger movement in either direction, and means for clamping said plate to said support, said plate having an integral extension cooperating with said support for maintaining said stop means of said plate in predetermined operative 10 positions relative to said trigger. 15
15. 3. A telephone coin collector comprising a coin passage, contacts for closing a central office circuit, means including an electromagnet for controlling from the central office the disposition of a coin upon passing through said passage, a pivotal armature for said electromagnet, a support for said armature, means for pivoting said armature on said support, a pivotal coin trigger having an arm projecting into said passage for operation by a deposited coin for closing said contacts, said trigger having a counterbalance, and a flat resilient plate adapted to be clamped to said support by said armature pivoting means having integral extensions providing resilient 20 stop means for said trigger for trigger movement in either direction. 25
20. 4. A telephone coin collector, comprising a coin passage, contacts for closing a central office circuit, means including an electromagnet for controlling from the central office the disposition of a coin upon passing through said passage, a pivotal armature for said electromagnet, a support for said armature, a shouldered member for pivoting said armature on said support, a pivotal coin trigger having an arm projecting into said passage for operation by a deposited coin for closing said contacts, said trigger having a counterbalance, and a flat plate composed of spring material adapted to be clamped between opposed 25
25. surfaces of said support and the shoulder of said armature pivoting member, said plate having integral leaf spring extensions providing resilient stop means for cushioning said trigger for trigger movement in either direction. 30
30. 5. In a telephone coin collector, a support, a coin trigger pivotally mounted thereon, and a cushioning device for said trigger, said device comprising a flat plate of resilient material having an integral arm extending in the plane thereof in a position to engage the trigger at the end of motion thereof in one direction and an integral arm extending angularly from the plate at substantially right angles to the first mentioned arm in a position to engage the trigger at the end of motion thereof in the other direction. 35
35. 6. In a telephone coin collector, a support, a coin trigger pivotally mounted thereon, a cushioning device for said trigger, said device comprising a flat plate of resilient material, an integral arm extending in a position to engage the trigger at the end of motion thereof in one direction and an integral arm extending in a position to engage the trigger at the end of motion thereof in the other direction, said support having two adjacent surfaces at an angle to each other and said plate having adjacent edges arranged at an angle to fit said surfaces, and means for securing the plate with said edges abutting said surfaces. 40
40. 7. A telephone coin collector comprising a coin passage, contacts for closing a central office circuit, means including an electromagnet for controlling from the central office the disposition of a coin upon passing through said passage, a pivotal armature for said electromagnet, a support for said armature having an angular extension, a headed screw for pivoting said armature on said support, a pivotal coin trigger having an arm projecting into said passage for operation by a deposited coin for closing said contacts, said trigger having a counterbalance, and a flat resilient plate adapted to be clamped between opposed surfaces of said support and the head of said armature pivoting screw, said plate having integral leaf spring extensions providing resilient stop means for cushioning said trigger for trigger movement in either direction, said plate having an integral extension and an edge cooperating with said angular extension of said support for maintaining said resilient stop means of said plate in predetermined positions relative to said trigger. 45
45. 50. WALTER A. BOCKISCH.
